UNITED STATES PATENT OFFICE

BERNARD R. SCHNEIDER, OF LYNDHURST, NEW JERSEY, AND KARL KAISER, OF NEW YORK, N. Y., ASSIGNEES TO AMERICAN CIGAR COMPANY, OF NEW YORK, N. Y., A CORPORATION OF NEW JERSEY

COUPON FOLDING MACHINE

Application filed October 22, 1929. Serial No. 401,542.

This invention is an improvement in coupon folding machines, and more particularly in a machine for folding the coupons to be fed by the coupon feeding machine forming the subject matter of application Serial No. 409,868, filed on Nov. 26, 1929, by Bernard R. Schneider and Karl Kaiser.

In the coupon feeding machine above referred to, folded coupons or the like, are positioned in cigar banding machines, at the spot upon which the operator places a cigar to be banded, thus enabling the applied band to enclose both the folded coupon and the cigar.

Articles of this nature whether coupons or advertising matter, are usually folded twice lengthwise, being fed in succession from the bottom of the pile of superposed coupons.

One of the primary objects of the present invention is the provision of feeding mechanism for withdrawing the lowermost of a pile of coupons, and for depositing it upon a pair of folding rollers, in position to be engaged by a folding blade.

Another object is to provide means in connection with such mechanism for positively separating the lowermost coupon in the magazine from those above, and for positively withdrawing it from beneath the pile.

Another object is the provision of folding blades and cooperating folding rollers, so arranged that a double fold will be imparted to the coupon as it travels past the rollers, the second mechanism being arranged to change the direction of travel of the coupon as it is folded.

Another object is the provision of mechanism for receiving the folded coupon from the last folding mechanism, and for positively delivering it to a receiving magazine.

Another object is the provision in connection with a pneumatic feeder for delivering the coupon from the last folding mechanism to the magazine of means for positively separating the coupon from the pneumatic feeder and positioning it in the magazine.

With these and other objects in view the invention consists in the construction and novel combination of parts fully described herein-after, illustrated in the accompanying draw-

ings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a front view of the improved machine.

Fig. 2 is a top plan view with parts in section.

Fig. 3 is an end view looking at the left of Fig. 2.

Fig. 4 is an enlarged detail in longitudinal section of one end of the machine.

Fig. 5 is a similar view of the other end.

Fig. 6 is a detail in side view.

Fig. 7 is a perspective view of the coupon in unfolded, partly folded, and completely folded condition.

In the present embodiment of the invention the improved machine comprises a suitable frame 1, having a pair of posts 2 arising therefrom, the posts being in a line longitudinal of the frame. Supported by the posts is a magazine, consisting of angular corner pieces 3 and 3a. Straps 4 are arranged at the sides of the magazine, between the corner pieces, and the coupons indicated at 5 are arranged in the magazine being supported at one end by lips 6 on the corner pieces 3a, and at the other by a cross rod 7 connecting the corner pieces 3. A bracket 8 supports the corner pieces 3—3a, and the straps 4, the bracket having bearings for receiving the posts 2.

A pneumatic device is provided for pulling down the left end of the lowermost coupon, as shown in Fig. 4. This device comprises a sucker head 9, extending transversely of the bottom of the magazine near the corner pieces 3a, and the sucker head has a longitudinally extending opening 10, from which lateral openings 11 lead to the top of the head, the openings being reamed at the top as shown in Fig. 4. The head is a part of a bracket 12, having bearings which are slideable on the posts 2, and the bore 10 is connected by a flexible hose 13 and a pipe 14 to

with a suitable exhaust mechanism, for creating a partial vacuum in the openings 11.

The bracket is reciprocated vertically through an eccentric cam groove 15a in the face of a gear wheel 15, to be later described, the bracket having a friction roller 16 moving in the groove. It will be apparent that when the gear wheel rotates, the bracket 12 will be reciprocated, and with it the bar or head 9, toward and from the magazine. The gear wheel has a stub shaft rotating in a bearing 17 on the frame 1, and it is driven by a gear wheel 18 on a shaft 19 journaled transversely of the frame, and connected with a suitable source of power by a belt 20a engaging a pulley 20 on the extended end of the shaft.

When the sucker head moves downwardly, the left end of the lowermost coupon is pulled downwardly, as shown in Fig. 4, and in order to insure the grip of the sucker head on the coupon, and the positive feeding thereof, a clamping lip or plate 21 is provided for engaging the coupon on the head, as it is being drawn into position on the folding rolls to be described.

The lip 21 is supported by a lever 22 pivoted at 23 to one end of a substantially U-shaped member 24. The other end of the member is loosely mounted on a shaft 25 journaled transversely of the frame. A link 26 connects the upper end of the lever 22 with a crank arm 27, also loose on the shaft 25.

By means of the U-shaped member and the link, a four feed movement is imparted to the lip. It is first moved into the position of Fig. 4, then downwardly with the sucker head, to the left from its position in Fig. 4, thence upwardly again to the right. Thus the lip is brought down upon the coupon on the sucker head, and moved with the sucker head, until the coupon is laid upon the folding rolls to be described. The movement of the lip is synchronized with the movement of the sucker head.

The U-shaped member 24 and the ring 26 are oscillated by means of cams 28 and 29, respectively, mounted on a shaft 30, which is journaled in the frame to the right and above the shaft 25. The cams engage friction rollers 31 and 32, respectively, on the member and the crank arm, and the parts are held in close engagement with the cams, by means of a spring 33, arranged between the crank arm 27 and an arm 34 in connection with a shaft 35. These parts will be later described.

The shaft 30 is driven from the stub shaft of the gear wheel 15, through intermeshing pinions 36, 37 and 38, the former being on the hub of the wheel 15, the latter on the shaft 30, and the gear 37 being an idler between the other two. A pair of folding rollers 39, 40 is arranged in the frame below the magazine. These rollers are secured on shafts 41,

42, the former being journaled in the frame, and the latter in bearing blocks 43, which are adjusted in guides 44 in the frame toward and from the shaft 41. The adjustment is by means of handle screws 45, mounted longitudinally of the frame at opposite sides of the magazine, and rotatably connected with the blocks. The screws have threaded connection with the frame, and it will be apparent that by turning them in opposite directions, the bearing blocks may be moved toward and from the shaft 41, whereby to properly position the rollers 39 and 40.

A folding blade 46 cooperates with the rollers 39-40, the said blade being mounted on an arm 47 secured to a shaft 48 journaled transversely of the frame. The shaft 48 is provided with a pinion 49 outside the frame, and the pinion meshes with a rack bar 50, mounted to reciprocate in guides 51 near the ends of the frame.

After leaving the folding rollers 39-40, which as shown in Fig. 5, are placed relatively close together, so that the fold is compressed, the coupon is fed downward between a pair of rollers 52-53, journaled in the frame below the rollers 39-40. The rollers 52-53 as shown, are spaced slightly further apart than the rollers 39-40, so that the folded coupon is received between them somewhat loosely, there being just sufficient grip of the rollers to hold the coupon firmly down against a stop 57 supported by the frame below the pairs of folding rollers 39-40 and 52-53, and in the plane of the contacting surfaces of the members of the pairs.

A folding roller 58 cooperates with the roller 52, the roller 58 being journaled just below the roller 52, and with its periphery contacting with the periphery of the roller 52. A folding blade 54 presses the once folded coupon between the cooperating rollers 52-58, to provide for the second fold. It will be noticed that the stop 57 is spaced so that when the first fold of the coupon rests thereon, the central portion of the coupon will be in line with the line of contact between rollers 52-58. The blade is secured to the upper end of an arm 55 secured to a shaft 56. This shaft is oscillated from the shaft 35 before mentioned.

The shaft 56 has a crank arm 59, connected by a link 60 with an elbow lever 61 upon the shaft 35. The arm 34 previously mentioned, is loose on the shaft 35, but is constrained to move therewith, and with the elbow lever, by the mechanism shown in Fig. 4. This mechanism comprises set screws 62, which are threaded through lugs 63 on the elbow lever 61, at opposite sides of the arm 34, and the relative position of arm and elbow lever may be varied by means of the set screws.

The shaft 35 is oscillated by means of a cam 64 on the shaft 30 before mentioned. This cam engages a roller 65 on the arm 34,

and the cam is substantially heart shaped, as shown. By means of the cam, the folding blade 54 is caused to push the once folded coupon between the rollers 52 and 58, to provide for a second fold, and the completely folded coupon is delivered by a feed arm 66 to a receiving magazine indicated generally at 67a.

The feed arm carries a sucker head 67, having a series of openings in the face thereof, which connect by passages 68, with a central bore 69 in a shaft 70 journaled in the frame adjacent the shaft 56. The bore 69 is connected with the exhausting apparatus, and as the twice folded coupon leaves the rollers 52-58, it is held to the suction head, the arm 66 being then in position of Fig. 4. The arm now moves to the position of Fig. 5, where the sucker head is in substantial alinement with the magazine. It will be noticed referring to Figs. 4 and 5 that the face of the sucker head is cut away at the side adjacent the rollers 52-58, to provide a shoulder 71 against which the second fold of the coupon abuts when the coupon leaves the rollers 52-58.

The receiving magazine as shown in Fig. 5, is trough shaped and extends beyond the end of the frame, being supported by an angle bracket 75 on the frame. The shaft 70 is oscillated by means of a rack bar 76 slideable in guides 77 on the frame, the rack bar engaging a pinion 78 on the shaft. The rack bar meshes with the teeth of a sector arm 79 loose on a shaft 80 journaled in the frame.

An elbow lever 81 is secured to the shaft, one of the arms thereof extending alongside the sector arm, and having lugs and set screws 82 similar to the set screws and lugs 62-63 previously described, for enabling the relative position of the elbow lever arm and the sector arm to be varied. A spring 83 is arranged between the sector arm and a bracket 84 on the frame, the spring acting normally to draw the sector arm and the elbow lever to the right of Fig. 1.

The other arm of the elbow lever has a friction roller bearing against a cam 85 on a shaft 86 journaled in the frame, and driven from the gear 36 through an idler 87 journaled on the frame, and a gear 88 secured to the shaft. When the elbow lever is rocked, the sector moves the rack bar, which in turn oscillates the shaft 70, and swings the delivery feed arm from the position of Fig. 4 to that of Fig. 5. The spring 83 holds the roller of the elbow lever against the edge of the cam.

Mechanism is provided for positively disengaging the coupon from the feeder head 67 and moving it into the magazine. This mechanism is in the form of an angle plate 89, one of the portions of which is secured to an arm 90 supported in a manner to be presently described. The other portion of the plate is adapted to engage the folded coupons

in the magazine. A follower 91 is arranged in the magazine to the right of the folded coupons, and as they are fed into the magazine, the follower is moved toward the right of Fig. 5. The plate 89 has a reciprocatory and lateral motion. That is, it is first lifted, then moved to the left and downwardly behind the coupon held by the head 67. It is then moved to the right, to press the received coupon against those already in the magazine.

This four feed motion is brought about by the mechanism shown at the extreme right of Fig. 5. A link 92 connects the arm 90 with a lever 93, which is secured to a shaft 94 journaled in bearing brackets 94a on the frame. The upper end of the link is journaled on the shaft, and the left end of the lever has a friction roller 95, which runs upon the edge of a cam 96 secured to the shaft 86. The link 92 has a lateral extension 97 provided with a friction roller 98 engaging the edge of another cam 99 on the same shaft. An adjustable link in the form of a turn buckle 100 connects the outer ends of the lever 93 and the arm 90.

As the shaft 86 rotates from the position of Fig. 5, the lever 93 will first be rocked to lower the outer end of the arm 90, and lift the angle plate 89. The link 92 will then swing inward, the roller 98 engaging the lower part of the cam 99, and the angle plate 89, still lifted, will be moved to the left of Fig. 5. The lever 93 will then be rocked to raise the outer end of the arm 90 and lower the plate 89, which at this time will be behind the folded coupon on the feeding head 67. The arm 90 will then be moved toward the right of Fig. 5, positively removing the folded coupon from the feeding head and moving it into the magazine, against the follower, or against the folded coupons already in the magazine.

The shaft 19 before mentioned, is provided with a sprocket wheel 101 outside of the frame, and a chain 102 connects the wheel with a wheel 103 on a shaft 104 journaled to the right of the rollers 39-52. The shaft has a pinion 105, which meshes with other pinions 106-107 on the shafts 52-58, respectively, so that the shaft 104 drives the rollers 39-52. This provides for the feeding of the coupon through the folding rollers. The lower run of the chain 102 is engaged by a tension wheel 110 on an arm 111 adjustable angularly of a shaft 112 held in the frame. The arm 111 is held in adjusted position by a set screw 113, passing through the arm and engaging the shaft.

The rack bar 50 is reciprocated by means of a toothed sector 120, mounted loosely on a shaft 121, and operated by an elbow lever 122, secured to the shaft. One of the arms of the elbow lever extends alongside the sector arm, and is provided with lugs and screws 130

123 and 124, corresponding to the lugs and screws 63—62, and for the same purpose, that is, for varying the relative position of the sector arm and the elbow lever. The other arm of the elbow lever is provided with a roller 125 which runs upon the edge of the cam 126, mounted on the shaft 30, before mentioned. This shaft also carries the cam 64 previously described.

10 It will be apparent that as the shaft 30 rotates, the elbow lever will be rocked, and the rack bar will be reciprocated, to oscillate the shaft 48 and the first folder blade 46. The roller 58 is adjustable toward and from the 15 roller 52. The ends of the roller 58 are journaled in bearing blocks 127, which are movable vertically in guides 128 in the frame. At the lower ends of the bearings are wedges or inclined cams 129, with which cooperate 20 wedges 130 movable transversely of the guides. The wedges 130 are operated by screw rods 131 journaled longitudinally of the frame. When the rods are turned, the wedges 130 will be moved laterally to raise or lower 25 the roller 58, that is, to adjust the said roller with respect to the roller 52.

Any suitable exhausting apparatus is provided for creating a vacuum in the openings of the pneumatic feeders 9 and 67. A valve 30 is provided for each feeder, each comprising a casing 140, and a valve 141 movable in the casing, the casings being secured to the frame as shown. A rocker 142 is pivoted to the frame intermediate its ends at each casing, 35 the pivotal connection being indicated at 143, and each rocker has rollers 144 at its ends. One of these rollers bears on the top of the valve, and the other upon the edge of a cam 145—146. The cam 145 is on the shaft 86, 40 while the cam 146 is on the shaft 30. One of the casings, namely: that adjacent the cam 145, is connected by a hose 147 with the pneumatic feeder 67, that is, with the bore 69 of the shaft 70. The other casing, that adjacent the cam 146, is connected by the pipe 14 before mentioned, with the pneumatic feeder 9. A pipe 150 connects the two casings.

Each valve has an annular port 151 near its lower end, and the pipes 150 and 14, or 150 and 147, are arranged opposite each other at the respective casings, as clearly shown in Fig. 6. When the valve is moved downward, the port 151 connects the exhausting apparatus with the pipe 14 or 147, as the case may be. It will be apparent that when the exhausting apparatus is connected with the pipe, there will be a partial vacuum created at the openings of the corresponding feeder, sufficient to hold the coupon in contact with the feeder.

The operation of the machine as a whole is as follows. A suitable supply of coupons being placed in the magazine, and the machine started, the pneumatic feeder 9 moves upward, and engages the end of the lowermost

coupon, after which it moves downward, pulling the said end free from the adjacent end of the magazine. At this moment the blade 21 is moved in upon the coupon, clamping the end of the same between the blade and the 70 feeder, and the blade continues to move downward with the feeder, until the coupon is completely disengaged from the magazine. The feeder moves on down with the blade, as indicated in dotted lines in Fig. 4, until the 75 coupon lies upon the rollers 39—40, with its transverse central line just above the contacting surfaces of the rollers. At this moment the folding blade 46 swings downwardly, and pushes the central portion of the coupon 80 between the rollers, which feed the coupon downward, pressing the fold. The coupon drops down between the rollers 52 and 53, which feed it down onto the stop 57, the folded edge of the coupon engaging the stop. 85

The rollers 52—53 are spaced, so that the folded edge of the coupon is just held against the stop, but without any downward pressure, more than sufficient to insure that it engages the stop throughout its length. The central portion of the once folded coupon is now opposite the contacting surfaces of rollers 52—58, and the blade 54 pushes the once folded coupon between the rollers 52—58, making the second fold. As it passes from between 90 the rollers, the partial vacuum in the openings 68 carry the coupon with the arm 66, which swings into the position of Fig. 5.

At this moment the blade 89 engages between the coupon and the feeding head 67, 100 and draws it into the magazine, into the position shown in Fig. 5. Referring to Fig. 2, it will be noticed that the blade 89 is forked, and the feeder head may have cutaway portions 160 through which the arms of the fork 105 pass to get behind the coupon.

What is claimed as new is:—

1. In a coupon folding machine, a magazine for superposed coupons, and feeding mechanism including means to depress one 110 end of the lowermost coupon, and other means to clamp the said end to the first named means, a pair of cooperating folding rolls arranged below the magazine across which the feeding mechanism lays the coupon, and a tucker for pushing the coupon between the rolls to fold it into double shape.

2. In a coupon folding machine, a magazine for superposed coupons, feeding mechanism including a sucker head for engaging 120 and pulling downward one end of the lowermost coupon, and a clamping member for clamping the said end to the sucker head, a pair of cooperating folding rolls arranged below the magazine across which the feeding mechanism lays the coupons, and a tucker for pushing the coupon between the rolls to fold it into double shape.

3. In a coupon folding machine, a magazine for superposed coupons, feeding mech- 125

- anism including a sucker head for engaging and pulling downward one end of the lowermost coupon, and a clamping member for clamping the said end to the sucker head, a pair of cooperating folding rolls arranged below the magazine across which the feeding mechanism lays the coupons, a tucker for pushing the coupon between the rolls to fold it into double shape, a second pair of folding rolls arranged with their axes in a plane at right angles to the first named pair, and a tucker cooperating with the second pair for pushing the once folded coupon between said rolls. 5
- 10 4. In a coupon folding machine, a magazine for superposed coupons, feeding mechanism including a sucker head for engaging and pulling downward one end of the lowermost coupon, and a clamping member for clamping the said end to the sucker head, a pair of cooperating folding rolls arranged below the magazine across which the feeding mechanism lays the coupons, a tucker for pushing the coupons between the rolls to fold it into doubled shape, a second pair of folding rolls arranged with their axes in a plane at right angles to the first named pair, a stop below the second named pair and in line with the cooperating surfaces of the first named 20 pair against which the folded coupon abuts, a tucker for cooperating with the second pair of folding rolls, and another roll cooperating with the topmost of the second pair of rolls and spaced apart therefrom to loosely engage the folded coupon to hold it against the stop. 25
- 25 5. In a coupon folding machine, means to once fold the coupon along a central line, means to feed the coupon to the folding means, a second folding means, a stop below the first named means against which the once folded coupon abuts, and means cooperating with the second folding means to loosely engage the folded coupon to hold it against the stop. 30
- 30 6. In a coupon folding machine, means to fold a coupon, a receiving magazine, mechanism to receive the folded coupon from said means and deliver it to the magazine, and means for positively removing the coupon from the delivering means and moving it into the magazine. 35
- 35 7. In a coupon folding machine, means to fold a coupon, a receiving magazine, mechanism to receive the folded coupon from said means and deliver it to the magazine, and means for positively removing the coupon from the delivering means and moving it into the magazine, the receiving mechanism including a sucker head, the last named means including a fork, the arms of which pass between the folded coupon and the sucker head. 40
- 40 8. In a coupon folding machine, means to fold a coupon, a receiving magazine, a sucker 45
- head for receiving the folded coupon and moving it toward the magazine, and means for stripping the coupon from the sucker head and moving it into the magazine. 50
- 50 9. In a coupon folding machine, a magazine, folding rolls having their axes in a plane perpendicular to that of the magazine, a tucker for moving a coupon between the rolls, mechanism to receive the coupon from the rolls and deliver it to the magazine, said mechanism including a sucker head mounted to swing through an angle of substantially 90°, whereby to carry the coupon from the folding rolls to the magazine, and a fork including a body and arms extending at an angle to the body, and means for imparting a four feed motion to the arm to insert the fork arms between the sucker head and the coupon to strip it therefrom, and to draw it into the magazine. 55
- 55 10. In a coupon feeding machine, a magazine for the coupons to be folded in which the coupons are arranged in superposed relation, a pair of folding rolls, and mechanism to remove the lowermost coupon from the magazine and lay it on the folding rolls, said mechanism including a sucker head for drawing down an end of the lowermost coupon, and a clamping lip engaging said end to clamp it on the head. 60
- 60 11. In a coupon feeding machine, a magazine for the coupons to be folded in which the coupons are arranged in superposed relation, a pair of folding rolls, and mechanism to remove the lowermost coupon from the magazine and lay it on the folding rolls, said mechanism including a sucker head for drawing down an end of the lowermost coupon, and a clamping lip engaging said end to clamp it on the head, and means for imparting a four feed motion to the lip to cause it to move between the end of the lowermost coupon and the superposed coupons, and to move downwardly with the sucker head. 65
- 65 12. In a coupon folding machine, a plurality of folding means, each including a pair of rolls and a tucker, a stop for positioning the once folded coupon with respect to the second pair of rolls, and means cooperating with one of said second pair to hold the coupon against the stop. 70
- 70 13. In a coupon folding machine, a plurality of folding means, each including a pair of rolls and a tucker, a stop for positioning the once folded coupon with respect to the second pair of rolls, and means cooperating with one of said second pair to hold the coupon against the stop, said means including a roll spaced apart from the first roll of the second pair for the purpose set forth. 75
